GEM-DINITROALKANEDIAMINES

Marvin H. Gold, Pasadena, Calif., and Levonna Herzog, Mountain View, N.J., assignors to Aerojet-General Corporation, Azusa, Calif., a corporation of Ohio
No Drawing. Filed Apr. 11, 1957, Ser. No. 652,305
5 Claims. (Cl. 260—583)

This invention relates to new compositions of matter and methods for producing the same, and is related in particular to geminal dinitro alkane diamine compounds having the general formula:

wherein A is a lower alkylene radical.

This application is a continuation-in-part of our co-pending United States patent application Serial No. 428,790, filed May 10, 1954, now abandoned, which was a continuation-in-part of our copending United States patent application Serial No. 210,626, filed February 12, 1951, now abandoned.

The diamines of this invention can be converted to their corresponding diols by the action of nitrous acid. The diols thus produced are useful in the preparation of polyurethane propellants, as disclosed in assignee's copending United States patent application Serial No. 422,649, filed April 12, 1954, now abandoned.

The diamines of this invention also react with beta-geminal dinitro alcohols such as trinitroethanol to form valuable high explosive compositions, as disclosed in assignee's copending United States patent application Serial No. 421,984, filed April 8, 1954, now abandoned. The high explosives thus formed can be used in any conventional explosive missile, projectile, rocket, or the like, as the main explosive charge. An example of such a missile is disclosed in United States Patent No. 2,470,162, issued May 17, 1949. One way of using the high explosives of this invention in a device such as that disclosed in United States Patent No. 2,470,162, is to pack the crystalline explosive in powder form into the warhead of the missile. Alternatively, the crystals can be first pelletized and then packed. A charge thus prepared is sufficiently insensitive to withstand the shock entailed in the ejection of a shell from a gun barrel or from a rocket launching tube under the pressure developed from ignition of a propellant charge, and can be caused to explode on operation of an impact- or time fuse-mechanism firing a detonating explosive such as lead azide or mercury fulminate.

The compositions of this invention are conveniently prepared by hydrolyzing a geminal dinitroalkane dicarbamate in the presence of a strong mineral acid and subsequently neutralizing the resultant diamine salt with an alkali or alkaline earth metal base in accordance with the general reaction scheme set forth below:

2

wherein R is an alkyl radical, A is an alkylene radical and X is the anion of a strong mineral acid.

The following examples are provided to more clearly illustrate the invention. It is to be understood that these examples are presented merely as a means of illustration and are not intended to limit the scope of the invention to the particular conditions set forth therein.

15

EXAMPLE I

Preparation of dimethyl-3,3-dinitro-1,5-pentanedicarbamate

A mixture of one mole of 3,3-dinitro-1,5-pentane diisocyanate and 1.5 liters of methanol was placed in a flask equipped with a reflux condenser. The alcohol reacted with the diisocyanate thus generating sufficient heat to bring the reaction mixture to reflux temperature. The reaction was allowed to proceed until substantially complete. Excessive methanol was removed by distillation and crystals of dimethyl-3,3-dinitro-1,5-pentanedicarbamate were collected on a Buchner funnel and recrystallized from chloroform. Pure dimethyl-3,3-dinitro-1,5-pentanedicarbamate was obtained as a white crystalline solid having a melting point of approximately 114° C. The yield was about 90 to 95% of theoretical.

EXAMPLE II

Preparation of 3,3-dinitro-1,5-pentanediamine dihydrochloride

Approximately 5.2 moles of dimethyl-3,3-dinitro-1,5-pentanedicarbamate dispersed in 5,000 ml. of concentrated HCl was placed in a flask equipped with a reflux condenser. The reaction mixture was refluxed for 16 hours and the hydrochloride salt which formed was removed by filtration. The hydrochloride salt was recrystallized from a mixture of 1250 ml. of methanol and 2500 ml. of water. The final product was recovered in an amount equivalent to about 70-75% of the theoretical amount; the melting point of the product was between about 228° and 235° C.

EXAMPLE III

Preparation of 3,3-dinitro-1,5-pentanediamine

To a stoichiometrically equivalent solution of sodium hydroxide in alcohol was added 3,3-dinitro-1,5-pentanediamine dihydrochloride and the whole then shaken. The resultant free diamine was separated from the mixture by filtration, as a colorless solid having a melting point of about 73-74° C.

The free diamine was further characterized by the preparation of the dibenzoyl and diacetyl derivatives by the reaction with benzoyl chloride and acetyl chloride. The dibenzamide melted at 144-145° C. and the diacetamide melted at 147° C.

The reaction temperature is non-critical in the practice of this invention, the only effect of temperature changes being corresponding increases or decreases in the rate of reaction. As a matter of convenience, it is preferred to conduct the hydrolysis reaction at reflux temperature.

The diisocyanates employed as starting materials in this invention, such as 3,3-dinitro-1,5-pentane diisocyanate, are prepared by reacting a gem-dinitro diacid halide, such as 4,4-dinitroheptanedioyl chloride, with an azide of an alkali or alkaline earth metal, such as sodi-

um azide, and heating the resulting product to effect rearrangement to the desired diisocyanate, as more fully disclosed in our copending United States patent application Serial No. 623,728, filed November 16, 1956.

By merely selecting an appropriate diisocyanate, such as 4,4-dinitro-1,7-heptane diisocyanate, and 5,5-dinitro-1,9-nonane diisocyanate and proceeding in accordance with the examples given above, a wide variety of homologues of this invention can be obtained, such as 4,4-dinitro-1,7-heptanediamine, 5,5-dinitro-1,9-nonanediamine, 10 etc.

We claim:

1. As new compositions of matter the geminal dinitro-alkanediamine compounds having the formula:

wherein A is a lower alkylene radical.

2. As a composition of matter, 3,3-dinitro-1,5-pentanediamine having the structural formula:

3. The method of preparing geminal dinitroalkane-diamine compounds having the formula:

5 which comprises hydrolyzing a geminal dinitroalkane-dicarbamate having the structural formula:

wherein A is a lower alkylene radical and R is a lower alkyl radical, in the presence of a strong mineral acid, and subsequently neutralizing the resultant diamine salt.

15 4. The method of preparing 3,3-dinitro-1,5-pentane-diamine which comprises hydrolyzing a dialkyl-3,3-dinitro-1,5-pentane-dicarbamate in the presence of a strong mineral acid and subsequently neutralizing the resultant diacid salt.

20 5. The method of preparing 3,3-dinitro-1,5-pentane-diamine which comprises hydrolyzing dimethyl-3,3-dinitro-1,5-pentane-dicarbamate in the presence of hydrochloric acid and subsequently neutralizing the resultant dihydrochloride salt with sodium hydroxide.
